[57] CLAIM

The ornamental design for a compact disc package, as shown and described.

DESCRIPTION

FIG. 1 is an isometric view of a compact disc package showing my new design;

FIG. 2 is a top plan view thereof, the bottom plan view being plain and unornamented;

FIG. 3 is a left side elevational view thereof;

FIG. 4 is a right side elevational view thereof;

FIG. 5 is a front elevational view thereof;

FIG. 6 is a rear elevational view thereof;

FIG. 7 is a isometric view of a second embodiment of FIG. 1;

FIG. 8 is a top plan view of FIG. 7, the bottom plan being plain and unornamented;

FIG. 9 is a left side elevational view of FIG. 7;

FIG. 10 is a right side elevational view of FIG. 7;

FIG. 11 is a front elevational view of FIG. 7; and,

FIG. 12 is a rear elevational view of FIG. 7.

FIGS. 1 and 7 are on a reduced scale.
